UNITED STATES PATENT OFFICE.

WINSLOW C. LEACH, OF CONKLIN FORKS, NEW YORK.

DESIGN FOR A SLEIGH.

SPECIFICATION forming part of Design No. 14,145, dated July 31, 1883.

Application filed June 6, 1883. Term of patent 7 years.

To all whom it may concern:

Be it known that I, WINSLOW C. LEACH, of Conklin Forks, Broome county, State of New York, have invented a new and Improved Design for a Sleigh, of which the following is a full, clear, and exact description.

My invention has reference to a sleigh in which the runners are made to form bows at their ends for connection directly with the body of the sleigh, without knees and beams.

Heretofore sleighs of this description have presented a bare and unsubstantial appearance, both when viewed laterally and endwise. My novel design does away with this and gives an ornamental as well as substantial appearance to the sleigh, that makes it more attractive.

The design consists in having the runner portion of the sleigh ornamented by a peculiar configuration and arrangement of braces extending from the base portion of each runner, at opposite ends thereof, to bars connecting the bow ends of the portions of both runners, substantially as hereinafter described.

Reference is to be had to the accompanying drawings, forming part of this specification, in which similar letters of reference indicate corresponding parts in both figures.

Figure 1 is a side view of a cutter-sleigh, showing my improved design; and Fig. 2 is an end view of the same.

A A are the usual bow-ended runners, made fast at their upper ends to the sills of the body B in the ordinary way. C C are the cross-bars connecting the two runners at their opposite

bowed ends at a suitable height from the bases of the runners, as at b b. D D are the braces connecting opposite end portions of the bases of both runners, as at c c, with the bars C C, at equal distances from the inside of each runner, as at d d. These braces are of a curved form or configuration, bowing in the same directions as the lower bowed-end portions of the runners, but of greater radius than said portions. Thus the braces D D, when viewed from either side of the sleigh, present a curved configuration, which is in perfect symmetry with the bowed ends of the runners, the same, too, inclining inward in an upward direction, which restricts them from too great prominence, as seen from the sides of the sleigh, and makes them also visible from the ends thereof in diverging directions toward the bases of the runners, with diminishing prominence in a downward direction from the bars C C, which are straight in contrast with the curved braces D D.

Having thus described my invention, I claim as new and desire to secure by Letters Patent—

The improved design for a sleigh having bowed-end runners, which consists of the straight cross-bars C C and the braces D D, made curved or bowing in an outward direction endwise, and inclining inward in an upward direction from the bases of the runners to the cross-bars, as shown and described.

WINSLOW C. LEACH.
